UNITED STATES PATENT OFFICE

115,810

DESIGN FOR A COMBINED LAVATORY LEG AND TOWEL BAR

Jean O. Reinecke and Joseph M. Kovarik, Jr.,
Chicago, and Roy H. Zinkil, Oak Park Ill., as-
signors to Crane Co., Chicago, Ill., a corpora-
tion of Illinois

Application May 20, 1939, Serial No. 85,093

Term of patent 14 years

To all whom it may concern:

Be it known that we, Jean O. Reinecke, Joseph M. Kovarik, Jr., and Roy H. Zinkil, citizens of the United States, the said Reinecke residing at 664 North Michigan Avenue, in the county of Cook, city of Chicago, State of Illinois; the said Kovarik residing at 5715 South Whipple Street, in the county of Cook, city of Chicago, State of Illinois; and the said Zinkil residing at 406 North Cuyler Avenue, in the county of Cook, village of Oak Park, State of Illinois, have invented a new, original, and ornamental Design for a Combined Lavatory Leg and Towel Bar, of which the fol-

lowing is a specification, reference being had to the accompanying drawing, forming part thereof.

Fig. 1 is a top plan view of a combined lavatory leg and towel bar embodying our new design.

Fig. 2 is a side elevation thereof.

Fig. 3 is a front elevation thereof.

We claim:

The ornamental design for a combined lavatory leg and towel bar, substantially as shown.

JEAN O. REINECKE.

JOSEPH M. KOVARIK, JR.

ROY H. ZINKIL.
